SHOE HEEL FEEDING MECHANISM

Justin P. Quirk, St. Louis County, and Ludwig G. P. Hafner, St. Louis, Mo., assignors, by mesne assignments, to Quirk Machinery Company, St. Louis, Mo., a corporation of Delaware

Application April 14, 1948, Serial No. 21,084

22 Claims. (Cl. 144—245)

1

This invention relates to a feeding mechanism for shoe heel machines.

In the art of making wooden shoe heels, the heel is first turned from a wooden blank which is jacked upon a rotatable spindle, the heel blank being moved into the path of a rotating cutter with relative complex motions to give the heel its desired shape. Thereafter, depending upon the machine used, the turned heel may be finished in a sanding machine which is similar to the turning machine with the exception that the turned heel is moved into the path of a moving sander. Heretofore the wooden blank or the turned heel, as the case may be, has been fed into the machine by a manual operation which is both time consuming, costly, hazardous, and sometimes inaccurate.

By means embodying the instant invention, the function of feeding the heel blank, or the turned heel, is accomplished automatically by mechanism briefly described as follows. A series of compressed air lines and air valves are connected and interconnected with a plurality of air cylinders and pistons to operate a jack by means of which the heel blank or heel is held in place on its rotating spindle; the engagement and disengagement of a clutch through which the spindle is rotated, the operation of a feeding mechanism which carries the heel blank, or heel, from a continuous supply source onto the jack, and an air ejector for removing the heel from the jack.

A master cam is mounted on the rotating spindle of the machine which is arranged for free movement thereon. This master cam is provided with two cam elements and a ratchet wheel segment by means of which latter element the master cam is turned on the spindle. An air valve which controls the supply of air to an air cylinder for operating the heel jack is controlled by a first of these cams. Similarly, the second cam operates a second air valve through which is controlled the supply of air to an air cylinder for operating the clutch. A third cam mounted on the spindle independently of the master cam operates an air valve which supplies compressed air to an ejector nozzle located in proximity to the jacked heel blank or heel.

Further, an air valve operated by the clutch operating mechanism, aforesaid, is provided to control the supply of air to an air cylinder which moves a pair of cam operated fingers in a manner such as to clamp a heel blank, or heel, and move the same onto the heel jack. Similarly, a trigger operated air valve mounted on the feeding mechanism, per se, is controlled by the move-

2

ment thereof to admit air into an air cylinder and move a piston operated ratchet pawl against the ratchet wheel segment carried on the master cam to move the same about the spindle.

5 Through the operation of these mechanisms, in timed sequence, a heel blank or a heel, which has just about completed its rotative cycle on the spindle, is operated on in the following manner. Just prior to the completion of a single revolution of the jack spindle, the jack is operated to release its clamping action on the heel blank, or heel. Thereafter, air is released from the ejector nozzle to eject the heel. Next, the clutch operating mechanism is activated to disengage the 10 clutch and the jack spindle is stopped. Thereafter, air is admitted to the piston controlling the feeding mechanism, per se, which moves a heel blank, or heel, onto the jack, which is shortly thereafter moved to clamp the blank or heel 15 therein. Operation of the feeding mechanism, per se, then causes air to be admitted into the ratchet pawl cylinder which effects the movement of the master cam on the spindle shaft. This movement of the master cam operates the jack to 20 clamp the heel or blank and also the clutch shifter to engage the clutch and start rotative movement of the jack spindle, thus completing the cycle. Previously to the engaging movement 25 of the clutch operating mechanism a valve is opened to bleed air from the feeding mechanism cylinder and permit the return of the fingers to 30 their normal starting position.

It may be stated, therefore, that the general object of the instant invention is to provide a 35 mechanism for feeding a shoe heel, or shoe heel blank, into a shoe heel machine which is entirely automatic in its operation, is adjustable, is simple in construction, economical to manufacture, operate and maintain, and one which is 40 positive in its action to the extent that waste is reduced to a minimum.

Other objects and advantages will become apparent as the specification proceeds, and a more comprehensive understanding of the invention 45 will be afforded from the following detailed description when considered in conjunction with the accompanying drawings, in which—

Fig. 1 is a schematic view of a feeding mechanism for a shoe heel machine embodying the 50 instant invention, with feeder unit, per se, disposed 90° from its normal position;

Figs. 2, 3 and 4 are top, front and end views, respectively, of a clutch operating mechanism forming a part of said feeding mechanism;

Figs. 5, 6 and 7 are front, end and top views,

respectively, of an air operated jack forming a part of said feeding mechanism;

Figs. 8 and 9 are top and side views, respectively, of the mechanism's shoe heel feeding unit, per se;

Fig. 10 is a front view of the mechanism's master cam showing the same mounted for rotation on the machine's jack spindle, and illustrating the mounting of its cam controlled air valves;

Fig. 11 is a plan view of the master cam's ratchet wheel segment and the ratchet operating mechanism which effects a movement of the master cam about the machine's jack spindle; and

Fig. 12 is a plan view of the machine's jack operating cam together with the air valve controlled thereby for supplying air to the jack cylinder.

As schematically illustrated in Fig. 1, the feeding mechanism, embodying the instant invention, is applied to a shoe heel machine, which may take the form of that illustrated and described in Patent No. 2,488,100, issued November 15, 1949, to Justin P. Quirk and Ludwig G. P. Hafner, for Shoe Heel Turning Machine, and which includes a jack seat 21 mounted for rotation upon a jack spindle 22 driven by a motor 23. In such a machine a heel blank 24 is clamped on the jack seat 21, and, while rotated on the seat, is moved with complex movements against a tool such as a rotating cutter 20 (not shown).

As pertains to the instant invention, the machine described in the aforementioned patent application, is modified to the extent of the inclusion of a clutch 25 through which rotation of the jack spindle 22 and the jack seat 21 by the motor 23 is controlled.

The principal component parts of the pneumatic feeding mechanism forming the subject matter of this invention, are a clutch operating mechanism 26, a pneumatic jack operating mechanism 27, a shoe heel feeding unit, per se, 28 and a control assembly cam 29. These various component parts of the composite shoe heel feeding mechanism will be described in the order named.

With reference to Figs. 2-4, inclusive, the clutch operating mechanism 26 includes a pair of fingers 31 which are mounted on a shaft 32 to be moved against a clutch disc 33 (Fig. 1) which, in turn, is moved against a continuously moving clutch element 34 to engage the clutch 25. The shaft 32, which moves the fingers 31, is attached to a clutch operating arm 35 and is supported for pivotal movement in a bracket 36. The arm 35 is biased by a spring 37 against a plunger 38 which has attached thereto a piston (not shown) contained for reciprocal movement in an air cylinder 39. The action of the spring 37 is such as to pivot the arm 35 to rotate the shaft 32 and move the fingers 31 to disengage the clutch 25. When air is acting in the cylinder 39, the plunger 38 is moved against the arm 35 to pivot the same against the action of the spring 37 and engage the clutch.

As an adjunct to the clutch operating mechanism 26, a leaf spring 41 is attached to the end of the arm 35 to be moved against a plunger 42 for operating a three-way air valve 43 secured to a base plate 44 as is the air cylinder 39 and associated elements. The function of the air valve 43 will be described later. However, it is to be pointed out that this valve is provided with an inlet 43a, an outlet 43b and a bleeder port 43c, the latter being open to atmospheric pressure.

The inlet 43a is connected by a suitable line to a compressed air manifold (not shown).

The pneumatic jack operating mechanism 27 is illustrated in Figs. 5-7, inclusive. It includes an air cylinder 45 in which a spring loaded piston (not shown) is operative to move a plunger 46 connected at one end to a pivotal link 47. The other end of the pivotal link 47 carries a pin 48 which is movable against a vertically movable arm 49 supporting a pin 51 bearing therein, as shown, for rotation. The arm 49 is vertically movable in the slides 52 against the forces of a compression spring 53 which acts to raise the arm 49 and the pin 51 for returning the arm 49 to its open position.

The pin 51 is provided with a beveled, serrated surface 54 which engages the top bevel of a heel, or blank, to clamp the same onto the jack seat 21. Inasmuch as it is required that this beveled surface be positioned at the end of each cycle of its turning movement so as to be aligned with a beveled surface 55 of the heel 24 (Fig. 1), provision is made to rotate the pin 51 to such normal position immediately upon the release of a heel from the jack. This mechanism comprises a tension spring 56 (Fig. 7) which is fixed at one end to the arm 49 by a pin 57 and which is attached at its other end to an off-center pin 58 mounted on the rotatable nut which holds the pin 51 in its bearings.

As will be apparent to those skilled in the art, it is required that the vertically movable elements of the jack must be provided with means for adjusting their positions relative to the jack seat to accommodate the jack for heels of different heights. Thus, it is required that the amount of clamping pressure applied by the pneumatically powered jack be the same for each heel and that any adjustment which is made to the jack must take this requirement into consideration. It is further imposed that any adjustment made to the jack be effected easily and quickly.

Accordingly, the air cylinder 45 is mounted on a base 59 attached to a slide 61, which is threaded to receive an adjustment screw 62 turned by a knob 63, as shown in Fig. 5. With this arrangement of the parts, and by turning the adjustment knob 63, the pin 51 may be raised or lowered relative to the jack seat 21 (Fig. 1) to accommodate for heels of different heights. Simultaneously with the movement of the base 59, which provides for such adjustment, the arm 49 is moved proportionately by means of two pins 64 fastened into the base 59, through the spring 53 acting against two pins 65 fastened to the arm 49 and, accordingly, the amount of pressure applied by the air cylinder 45 and its associated mechanisms to the pin 51 in clamping a heel between its surface 54 and the jack seat 21 remains constant and unaffected.

The heel feeding unit, per se, 28 is illustrated in Figs. 8 and 9 and the same will be described now in detail. A base 67 is provided for the heel feeding unit, which base is rigidly attached to a portion of the shoe heel machine. Upon this base is mounted, by means of a covering bracket 68, a prepositioning platform 68'. Carried beneath the cover plate 68 are two pivoted clamping members 69 and 71. These members are so arranged that they slide between the base 67 and the cover plate 68 with reciprocal movement, that movement being imparted by means of a plunger 72 connected to a piston (not shown) acting within an air cylinder 73. Attached to a movable plate 74, upon which the members 69 and 71 are

pivoted, respectively, at the points 75 and 76, are two tension springs 77 and 78. These springs are operative to bias the clamping members 69 and 71 rearwardly as viewed in Fig. 8 against forces developed in the air cylinder 73, which forces are operative to move the plate 74 and the members 69 and 71 forwardly to place a heel blank on the jack seat 21.

Two springs 79 and 81 are mounted as shown in Fig. 8 which pivot the clamping members 69 and 71 about their respective pivot points 75 and 76 to move a clamping jaw 82, mounted on the member 69, and a clamping jaw 83 mounted on the member 71, into the heel blank to hold the same tightly when it is carried forward to the jack seat 21 by the forward movement of the members 69 and 71.

As the clamping members 69 and 71 are returned from their furthermost forward position under the action of the springs 77 and 78, it is required that the clamping jaws 82 and 83 carried thereon be moved outwardly to clamp the next heel blank which is to be placed on the jack 21. To perform this function, a pair of upright cams 84 and 85 are secured to the base 67 as shown, and against these cams are moved, respectively, a cam follower 86 and a cam follower 87 secured, respectively, to the ends of the members 69 and 71. The cam followers 86 and 87 are spring-biased to a normal position and are secured to their respective members to rotate about a pin 88 and a pin 89, respectively. When the members 69 and 71 are moved rearwardly under the action of the springs 77 and 78, the bevelled cam faces 91 and 92 of the cam followers 86 and 87, respectively, are held in position as shown in Fig. 8 by two stops 93 and 94. These stops are secured, respectively, to the members 69 and 71. Accordingly, the cam faces 91 and 92 are presented to the cam faces of the cams 84 and 85 to pivot the members 69 and 71 about their pivot points 75 and 76 to open the jaws 82 and 83 for a period of time equivalent to that consumed by the travel of the cam followers 86 and 87 along the cams 84 and 85, respectively. After the cams are passed, the jaws 82 and 83 are returned to a clamping position to secure the next heel fed onto the prepositioning platform 68', as shown in Fig. 9. On the forward stroke of the members 69 and 71, the cam followers 86 and 87 pivot about their respective points 88 and 89 and are, therefore, positioned to pass the cams 84 and 85 without effecting any pivotal movement whatsoever to the members 69 and 71.

As illustrated in Fig. 9, the prepositioning platform 68' is provided at one end with a spring biased stop member 96 which is depressed out of the way when a heel is carried forwardly thereover, but which is positioned to arrest the movement of a heel in proper position on the platform 68' for clamping by the jaws 82 and 83.

It is to be pointed out that no provision is made for the opening of the jaws 82 and 83 at the furthermost point of the delivery stroke. These jaws may take the form of knife edges and, accordingly, it is not required that they be opened prior to the return stroke of the members 69 and 71 since they slide along the outer surfaces of the heel blank in which they are engaged to free themselves from the same.

The control of the clutch operating mechanism 26 and the jack operating mechanism 27 is effected by the master cam which is mounted on the jack spindle 22 and shown in detail in Fig. 10. The master cam 97 comprises a sleeve-like ele-

ment on which a clutch operating cam 98 and a jack operating cam 99 are formed, the latter cam being more particularly illustrated in Fig. 12. This sleeve-like element also carries a ratchet wheel segment 101 as a part of the master cam. The master cam 97 is mounted for restricted movement on the jack spindle 22, the same being free to turn thereabout for a partial revolution, measured by an angular distance through which a lug 102 secured to the jack spindle 22 will move in a slot or window 103 in the sleeve portion of the master cam. As thus arranged, a counterclockwise movement of the jack spindle 22 moves the lug 102 against an end 104 of the slot 103 and turns the said master cam 97 with the spindle until the latter is stopped. From this point, the master cam is free to be turned about the spindle 22 for a measured distance in a counterclockwise direction which will bring an end 105 of the slot 103 against the lug 102. The purpose of this movement and the means by which it is effected will be described in greater detail later.

Another cam 106, which controls the flow of air to an ejector nozzle 107 (Fig. 1), is also mounted for rotation on the jack spindle 22. This cam has formed thereon a cam segment 108 which is moved against a plunger 109 of two-way air valve 111 to feed compressed air through a line 112 (Fig. 1) to the ejector nozzle 107, aforesaid, the valve 111 being adapted to receive compressed air through a line 110 connecting with the manifold previously mentioned.

In a similar manner, the cam 98 of the master cam 97 is moved against a plunger 113 (Fig. 10) of a three-way air valve 114 which controls the flow of air through a line 115 (Fig. 1) to the air cylinder 39 of the clutch operating mechanism 26. Here also, the valve 114, which is supplied compressed air from a manifold through a line 115a, is provided with a bleeder port 114a open to atmospheric pressure.

As viewed in Fig. 12, the cam 99 has a depression 116 in the face thereof into which a cam follower 117 may fall as shown in the figure. A cam face 118 is provided against which the cam follower 117 rides to move an arm 121 against a plunger 122 of a normally closed three-way air valve 123 to maintain the same in an open position and operate the jack into its clamping position. When the cam follower 117 falls into the depression 116, the valve closes and the jack is opened. The valve 123, through a line 124 (Fig. 1), supplies compressed air to the cylinder 45 of the jack operating mechanism 27, which it receives from a manifold through a line 124a (Fig. 12). A bleeder port 123a is opened to atmospheric pressure to bleed the line 124 and the air cylinder 45 when the valve is closed.

For moving the master cam 97 on the jack spindle 22, as above described, an air powered ratchet mechanism 125 (Figs. 10 and 11) is provided, which is under the control of a three-way air valve 126 operated by the heel feeding unit, per se, 28. The air valve (Fig. 9) is secured to the underside of the base 67 of the unit 28 and has as a part thereof a pivoted trigger 127 (Fig. 9) which has an extension 128 engaging in a slot 129 in the plunger 72. The air valve 126, which is normally closed, is situated to be operated by the plunger 72 of the feeding unit 28 when the same is carried forward to the end of its feeding stroke. This action trips the trigger 127 to open the air valve 126 and supply air received from a compressed air manifold through a line 75 130 (Fig. 1) to the air powered ratchet mecha-

nism 125, previously mentioned by way of a line 131.

This latter device, which takes the form of a spring return, single acting air piston, will be explained with the aid of Figs. 10 and 11. It comprises an air cylinder 132 in which a piston (not shown) acts to move a plunger 133 to which is attached a pivoted ratchet pawl 134. Against this latter element, a spring 135 is active to move the same about its pivot point 136 and into engagement with the teeth of the ratchet wheel segment 101. Movement of the plunger 133 carries the ratchet pawl 134 forward, turning the master cam 97 on the jack spindle 22.

Operation

For the purpose of describing the operation of the feeding mechanism it will be assumed that a supply of heel blanks are fed by a suitable conveyor 137 (Fig. 9) to the feeding mechanism 28. It will be assumed further that the cycle of operation for descriptive purposes will start at the point where the feeder unit 28 is at the end of its full stroke as shown in Fig. 9 to deliver a heel blank A onto the heel jack 21.

At this point the slot 129 in the plunger 72 engages the trigger 127 which opens the normally closed air valve 126 to admit air through the line 131 to the air powered ratchet mechanism 125. Thereupon, the ratchet pawl 134 is carried forward to engage the ratchet wheel segment 101 of the master cam 97 and move the same from its position shown in Fig. 10 to a point where the end 105 of the slot 103 is moved against the lug 102. This action, that is the rotative movement of the master cam 97, causes movement in a counterclockwise direction of the cam 98 which moves the same to open the normally closed air valve 123 and admit compressed air through the line 124 to the air cylinder 45 of the jack operating mechanism 27. This clamps the delivered heel A between the surface 54 of the pin 51 and the heel jack seat 21. Also, valve 114, which is normally open, but which is now closed, is opened by the rotation of the cam 98 whereby admitting air to the air cylinder 39 of the clutch operating mechanism 26. Upon this action the clutch operating arm 35 is moved by the plunger 38 to engage the clutch 25. Prior to the engagement of the clutch, however, the movement of the arm 35 under the action of the plunger 38 is such as to move the leaf spring 41 away from the plunger 42 of the air valve 43 and the valve closes releasing air through the bleeder port 43c from the feeder mechanism cylinder 73. This permits the feeding members 69 and 71 to return to their normal position under the action of the springs 77 and 78 before the clutch 25 is engaged. The initial return movement of the plunger 72 permits the valve 126 to close and bleed the cylinder 132 through the bleeder port 126a, permitting the return movement of the ratchet pawl 134.

Approximately 45 degrees before the end of one full revolution of the spindle 22, the master cam effects the closing of the air valve 123 which bleeds through its port 123a the jack operating mechanism, and opens the jack to release the heel. The opening of the jack is followed by an opening of the valve 111 by means of the cam 106, which releases a blast of air from the ejector nozzle 107 to thereby eject the heel A. Upon completion of the turn, the air valve 114 is closed to release air through its bleeder port 114a from the cylinder 39, whereupon the spring 37 moves the arm 35 rearwardly to disengage the clutch. As

the arm 35 of the clutch operating mechanism continues its rearward movement after the disengagement of the clutch 25 to stop rotation of the jack spindle 22, the air valve 43, which is normally closed, is opened to admit air through the line 138 to the feeder operating mechanism air cylinder 73. This causes the feeding members 69 and 71 to move forward and carry a second heel blank B (Fig. 9) onto the jack seat 21, and the cycle of operation is repeated.

Various changes may be made in the details of construction, within the scope of the appended claims, without departing from the spirit of this invention. Parts of the invention may be used without the whole and improvements may be added while retaining some or all of the advantages of the invention.

What is claimed is:

1. In a feeding mechanism for a shoe heel machine having a jack seat mounted for rotation on a rotatable spindle and a motor for driving said spindle through a clutch, the combination comprising a clutch operating mechanism, an air cylinder and a piston for moving said clutch operating mechanism to engage and disengage said clutch, a jack clamp movable relative to said seat to clamp a heel therebetween, an air cylinder and piston for moving said jack clamp, an ejector nozzle adapted to exhaust an air jet against a heel released from said jack clamp and seat, a cam operated heel feeder clamp adapted to grasp a heel, a feeder cylinder and piston adapted to operate said heel feeder clamp to move a heel onto said jack seat, a master cam mounted on said jack spindle for restricted free movement thereabout and to be turned by said spindle, first and second cams and a ratchet wheel segment formed on said master cam, first and second air valves operated by said first and second cams to control a flow of compressed air through suitable connective lines to said jack operating cylinder and to said clutch operating cylinder, a third cam mounted on said spindle, a third air valve operated by said third cam to control air to said ejector nozzle, an air cylinder and piston for moving a ratchet pawl against said ratchet wheel segment on said master cam to turn the latter on said jack spindle, an air valve operated by movement of said feeder piston to control the flow of compressed air to said ratchet operating cylinder, and an air valve operated by said clutch operating mechanism to control the flow of compressed air into said feeder cylinder.

2. In a feeding mechanism for a shoe heel machine having a spindle mounted heel jack and a motor for rotating said jack and said spindle through a clutch, the combination comprising an air powered jack operating mechanism, an air powered clutch operating mechanism for engaging and disengaging said clutch, an air powered heel feeding unit adapted to move a heel blank into position for clamping in said jack, an air ejector nozzle situated with respect to said jack to eject a heel released from said jack by an air jet, a cam assembly carried on said spindle comprising a master cam mounted on said spindle to turn therewith and to be moved thereabout with a restricted free movement and an independently mounted cam, an air powered reciprocating device for imparting restricted movement to said master cam to turn the same on said spindle, a plurality of air valves operated by said master cam and said independently mounted cam to control the flow of compressed air from a source through suitable connecting lines to said jack

operating mechanism, said clutch operating mechanism and said ejector nozzle, an air valve controlled by the movement of said heel feeding unit to control the flow of air to said reciprocating device, and an air valve operated by said clutch operating mechanism to control the flow of compressed air to said heel feeding unit.

3. In a feeding mechanism for a shoe heel machine having a rotatable jack mounted for rotation on a spindle driven by a power source through a clutch, a pneumatic jack operating mechanism, a pneumatic clutch operating mechanism and an air powered heel feeding unit, the combination comprising a master cam mounted on said jack spindle to be turned thereby and for restricted movement thereabout, a plurality of air valves operated by said master cam adapted to control the flow of compressed air to said jack and said clutch operating mechanisms, and a pneumatic ratchet under the control of an air valve operated by said heel feeding unit adapted to turn said master cam through a partial revolution to initiate movement of said clutch operating mechanism and said jack operating mechanism whereby said jack and said jack spindle are placed in rotation through the engagement of said clutch after a period of rest during which a heel is clamped in said jack.

4. In a shoe heel machine having a jack seat, the combination of an air operated jack clamp comprising a pin for engaging the end of a heel blank, an arm mounting said pin arranged for movement relative to said jack seat, a pivotal link for moving said arm relative to said seat, an air piston connected at one end to said link and retained in an air cylinder for reciprocating movement therein, and a screw for adjusting the relative position of said arm, said link, said piston and said air cylinder with respect to said jack seat whereby said jack seat and clamp may be accommodated to receive heels of different heights without affecting the magnitude of clamping pressure transmitted through said rotatable pin to said heel as applied by said air piston and cylinder.

5. In a feeding mechanism for a shoe heel machine having a jack seat mounted for rotation on a rotatable spindle, a motor for driving said spindle through a clutch, and an air operated shoe heel feeding unit, the improvement of a clutch operating mechanism comprising a clutch finger mounted for pivotal movement, a clutch operating arm, an air piston reciprocally movable in an air cylinder, a plunger attached to said piston and movable against said arm, a spring for biasing said arm against said plunger, a cam controlled air valve for supplying air to said cylinder, a master cam on said spindle for operating said air valve, an air powered ratchet mechanism for turning said master cam on said spindle to effect operation of said valve, and an air valve operated by said feeding unit to control the flow of air to said ratchet mechanism.

6. In a feeding mechanism for a shoe heel machine having a rotatable jack including a jack seat, the combination comprising a pair of spring biased pivoted jaws having clamp members attached thereto to receive a heel blank therebetween, a cam follower attached to each end of said jaws, each adaptable to be moved against a rigid cam to pivot said jaws into open position, an air piston contained for reciprocating movement in an air cylinder for moving said jaws on a base supporting the same to deliver a heel to said seat, and a pair of springs connected to said

base for applying a force thereto opposed to that of said air piston for moving said base and said jaws away from said seat.

7. In a feeding mechanism for a shoe heel machine having a jack mounted for rotation on a rotatable spindle and a motor for driving said spindle through a clutch, the combination comprising a jack operating device, a clutch operating mechanism, an automatic ejector for removing a heel released from said jack, a reciprocating heel clamp for moving a heel from a supply source into said jack, first and second cam operated control devices for controlling the operation of said jack operating device and said clutch operating mechanism, a master cam mounted on said spindle to be turned thereby and to be turned thereabout for operating said first and second control devices, a power operated ratchet mechanism for turning said master cam on said spindle, a third control device for operating said automatic ejector, a cam mounted on said spindle independently of said master cam for operating said third control device, a fourth control device operated by said reciprocating heel clamp for controlling the operation of said ratchet mechanism, and a fifth control device operated by said clutch operating mechanism for controlling the operation of said reciprocating heel clamp.

8. In a feeding mechanism for a shoe heel machine having a rotatable jack mounted for rotation on a spindle driven by a power source through a clutch, a jack operating device, a clutch operating mechanism and a reciprocating heel clamp adapted to move a heel from a source of supply onto said jack, the combination comprising a master cam mounted on said jack spindle to be turned thereon and for restricted movement thereabout, first and second control devices operated by said master cam and respectively adapted to control the operation of said jack operating device and said clutch operating mechanism, a power operated ratchet for turning said master cam on said jack spindle, and a third control device operated by said reciprocating heel clamp for controlling the operation of said ratchet to turn said master cam on said spindle and initiate movement of said clutch operating mechanism and said jack operating device, whereby said jack and said jack spindle are placed in rotation through the engagement of said clutch after a period of rest during which a heel is clamped in said jack.

9. In a shoe heel machine having a jack including a jack seat, the combination comprising a pin for engaging the end of a heel, an arm mounting said pin arranged for movement relative to said jack seat, a pivotal link for moving said arm relative to said seat, a power device connected to one end of said link, and means for adjusting the relative position of said arm, said link and said power device with respect to said jack seat whereby said jack may be accommodated to receive heels of different heights without affecting the magnitude of the clamping pressure transmitted to said heel by said power device.

10. In a feeding mechanism for a shoe heel machine having a jack seat mounted for rotation on a rotatable spindle, a motor for driving the spindle through a clutch and a reciprocating heel clamp adapted to move a heel from a source of supply onto said jack seat, the improvement of a clutch operating mechanism comprising a clutch finger mounted for pivotal movement, a

clutch operating arm; a power operated plunger movable against said arm, a spring for biasing said arm against said plunger, a cam operated control device for controlling the movement of said plunger, a master cam mounted on said spindle to turn thereabout and operate said cam operated control device, a power operated ratchet for turning said master cam on said spindle, and a control device operated by said reciprocating heel clamp for controlling the operation of said power operated ratchet.

11. In a feeding mechanism for a shoe heel machine having a rotatable jack mounted for rotation on a spindle turned from a power source through a clutch under the control of a clutch operating mechanism, the combination comprising a clamp arranged to select a single heel from a source of supply and clamp the same therein, first and second power devices for moving said clamp toward said jack for delivering a heel thereto and away from said jack, and a control device operated by said clutch operating mechanism for controlling the operation of said first power device.

12. In a feeding mechanism for a shoe heel machine having a jack mounted for rotation on a spindle, the improvement of a heel ejector adapted to clear said jack and condition the same to receive a heel blank comprising an air nozzle located in proximity with said jack, an air valve for controlling a flow of compressed air to said nozzle, and a cam mounted on said spindle adapted to open said valve and cause a blast of air to issue from said nozzle against a heel after the same has been released from said jack.

13. In a feeding mechanism for a shoe heel machine having a jack, including a jack seat and a jack clamp, the combination of a reciprocating heel clamp adapted to move a heel from a source of supply onto said jack seat, a power device for moving said jack clamp relative to said jack seat, an automatic heel ejector associated with said jack and separate control devices for said reciprocating heel clamp, said power device and said automatic heel ejector operated in timed sequence whereby a heel is placed on said heel seat is first clamped thereon, next released and then ejected therefrom by said automatic ejector.

14. In a feeding mechanism for a shoe heel machine having a jack mounted for rotation on a spindle driven through a clutch controlled by a clutch operating mechanism adapted to start and stop rotation of said spindle, the combination comprising a reciprocating heel feeder clamp operable to select a heel from a source of supply and deliver the same to said jack, and a control device for said reciprocating heel feeder clamp operated by said clutch operating mechanism, whereby said heel feeder clamp is made operative to deliver a heel on to said jack when said clutch is disengaged.

15. In a heel feeding mechanism for a shoe heel machine having a power operated jack adapted to clamp and release from clamping a heel therein, the combination comprising an automatic ejector associated with said jack, a first cam operated control device controlling the operation of said power operated jack, a second cam operated control device for controlling the operation of said automatic ejector, and a first and second independently movable cam for operating said first and second control devices.

16. In a feeding mechanism for a shoe heel machine having a jack mounted for rotation on a jack spindle which latter element is driven

through a clutch controlled by a clutch operating mechanism, the combination comprising a cam operated control device for controlling the operation of said clutch operating mechanism, a cam mounted on said spindle to be turned thereby and to be turned thereon, and a power device adapted to turn said cam on said spindle whereby said control device is conditioned to initiate movement of said clutch operating mechanism, engage said clutch, and start rotation of said spindle from a position of rest.

17. In a feeding mechanism for a shoe heel machine having a jack mounted for rotation on a spindle driven through a clutch which is operated by a clutch operating mechanism, a reciprocating heel feeder adapted to move a heel onto said jack and a cam operated control device for controlling the operation of said clutch operating mechanism, the combination comprising a first control device operated by said reciprocating heel feeder for controlling the operation of said cam operated control device, and a second control device operated by said clutch operating mechanism for controlling the operation of said reciprocating heel feeder.

18. In a feeding mechanism for a shoe heel machine having a power operated jack mounted for rotation on a spindle, a reciprocating heel feeder adapted to move a heel into said jack, an automatic ejector associated with said jack and a motor for rotating said spindle through a clutch which is engaged and disengaged by a clutch operating mechanism, a control system for said feeding mechanism, comprising a master cam mounted on said spindle to be turned thereby and to be turned thereon, a first control element and a second control element operated by said master cam to control respectively the operation of said jack and said clutch operating mechanism, a cam mounted on said spindle independently of said master cam, a third control element operated by said last mentioned cam for controlling the operation of said automatic ejector, a turning device for rotating said master cam on said spindle, a fourth control element operated by said reciprocating heel feeder for controlling the operation of said turning device, and a fifth control element operated by said clutch operating mechanism to control the operation of said reciprocating heel feeder.

19. In a feeding mechanism for a shoe heel machine having a rotatable spindle upon which a heel is jacked for rotation by a motor, the combination comprising a clutch interposed between said motor and said spindle, a clutch operating mechanism adapted to engage and disengage said clutch, a control device for controlling the operation of said clutch operating mechanism, a cam mounted on said spindle to be turned thereby and to be turned thereabout for operating said control device, and a turning device for rotating said cam on said spindle when the latter is at rest to initiate operation of said clutch operating mechanism and start rotation of said spindle.

20. In a feeding mechanism for a shoe heel machine having a rotatable jack including a heel seat, the combination comprising a prepositioning platform having a releasable stop, a heel clamp constructed and arranged to grasp a heel positioned on said platform, and means for reciprocating said clamp whereby the heel grasped as aforesaid is moved from the platform to the heel seat.

21. In a feeding mechanism for a shoe heel machine having a rotatable jack including a heel

seat, the combination comprising a prepositioning platform having a releasable stop, a heel clamp constructed and arranged to grasp a heel positioned on said platform, means for reciprocating said clamp whereby the heel grasped as aforesaid is moved from the platform to the heel seat, driving mechanism for rotating the jack; and a device operated by said mechanism for controlling said reciprocating means.

22. In a feeding mechanism for a shoe heel machine having a rotatable jack including a heel seat, the combination comprising a prepositioning platform having a releasable stop, a heel clamp including a pair of pivoted jaws adapted to grasp a heel positioned on the platform, a 15 spring for closing said jaws, cams for opening said jaws, and means for reciprocating the clamp

whereby a heel grasped as aforesaid is moved to the heel seat.

JUSTIN P. QUIRK.
LUDWIG G. P. HAFNER.
